UNITED STATES PATENT OFFICE.

FRANK STULLER, OF RIVESVILLE, WEST VIRGINIA.

SWORD-HILT PISTOL.

1,384,644.

Specification of Letters Patent. Patented July 12, 1921.

Application filed October 11, 1920. Serial No. 415,966.

To all whom it may concern.

Be it known that I, FRANK STULLER, a citizen of Jugo-Slavia, residing at Rivesville, in the county of Marion and State of West Virginia, have invented new and useful Improvements in Sword-Hilt Pistols, of which the following is a specification.

This invention has reference to weapons in which a sword and pistol are combined.

10 The primary object is to provide an automatic pistol with a shield between the barrel and grip thereof and with a socket whereby to receive the blade of a sword, means being provided for securing said 15 blade in the socket, the particular and peculiar construction of the guard permitting the sword to be wielded and the pistol to be fired as occasion requires.

A further object is the production of an 20 article of this character which shall be light in weight, simple in construction, and inexpensive to manufacture.

The foregoing, and other objects which will appear as the nature of the invention is 25 better understood, may be accomplished by a construction, combination and operative arrangement of parts, such as is illustrated by the drawings which accompany and which form part of this application.

30 In the drawings:—

Figure 1 is a side elevation illustrating an automatic pistol constructed in accordance with this invention and having a sword blade attached thereto.

35 Fig. 2 is a similar view but looking toward the opposite side of the weapon.

Fig. 3 is an end view.

Fig. 4 is a longitudinal sectional view 40 through the socket which is integrally formed on the pistol, and illustrating the spring actuated means for holding the sword blade therein, parts of the latter being in section.

Fig. 5 is a sectional view approximately 45 on the line 5—5 of Fig. 4.

The pistol 1 illustrated by the drawings may be of any well known automatic construction, and as the interior arrangement thereof, as well as the mechanism for exploding a cartridge and ejecting the same for such explosion as well as the means for feeding the cartridges from the mechanism into the barrel, do not form the subject matter of this invention, a detail description thereof will not be attempted.

On the grip or handle 2 of the pistol 1, at the outer or lower corner thereof there is formed the rounded portion 3 of the guard 4. The straight arm 5 of the guard is integrally formed with the extension 6 for the guard 7 for the trigger 8. The guard provides a means whereby the pistol cannot be accidentally removed from the hand of the user.

On one side of the barrel of the pistol there is formed an outwardly extending angularly arranged socket 9. The socket has its side walls provided with openings 10 through which are passed lugs 11 formed adjacent the outer ends of flat springs 12. The inner ends of these springs are secured, as at 13 to the sides of the socket, and the outer or free ends of the springs are rounded upon themselves to provide finger grips 14.

The blade of a sword is indicated by the 75 numeral 15. The blade has its inner edge flattened in the usual manner and is of a size to be snugly received in and contact with the walls of the socket. The blade is provided with notches 16 which, when the 80 blade is fully inserted in the socket are in alinement with the openings that receive the lugs 11, and the springs 12 will automatically force the lugs into engagement with the said notches, thereby effectively holding 85 the blade on the pistol.

By reference to the drawings, it will be noted that the socket being arranged at one side of the pistol does not interfere with the sighting of the weapon. The guard, as 90 previously stated prevents the accidental removal of the weapon from the hand of the soldier, so that the blade can be effectively wielded. The pistol being of the automatic construction can be fired a number of times 95 and the arrangement of the guard on the pistol does not interfere with the entrance passage in the grip of the pistol for the cartridge containing magazine.

It is thought that the foregoing description, when taken in connection with the drawings will fully set forth the construction and advantages of the improvement without further detail description.

Having thus described the invention, what 105 I claim, is:—

1. A pistol having a guard between the grip and barrel thereof, a socket on one side of the pistol projecting beyond the barrel and designed to receive therein the blade of 110

a sword, and means carried by the socket and engaging the sword blade for holding the same in the socket.

2. A pistol having a guard formed between the outer and lower corner of its grip and its barrel, an outwardly projecting upwardly disposed angularly arranged socket upon the barrel of the pistol, spring influenced lugs entering the sides of the socket, and the springs for said lugs having their

outer ends rounded to provide finger grips, and said socket designed to receive therein the end of a sword blade which is formed with notches to be engaged by the spring pressed lugs.

In testimony whereof I affix my signature.

FRANK STULLER.
